UNITED STATES PATENT OFFICE

147,891

DESIGN FOR A DINING BAR

Vera J. Crawford, Washington, D. C.

Application March 6, 1946, Serial No. 127,137

Term of patent 14 years

(CL. D33—14)

To all whom it may concern:

Be it known that I, Vera J. Crawford, a citizen of the United States of America, residing in the city of Washington, District of Columbia, have invented a new, original, and ornamental Design for a Dining Bar, of which the following is a specification, reference being had to the accompanying drawing, forming a part thereof.

In the drawing:

Fig. 1 is a plan view of a dining bar showing my new design.

Fig. 2 is a front elevational view of the same.

Fig. 3 is an end elevational view of the same, and

Fig. 4 is a sectional view taken on the line 4—4 of Figure 3.

Fig. 5 is a bottom plan view of the same.

Fig. 6 is a front perspective view of the same.

I claim:

The ornamental design for a dining bar, as shown.

VERA J. CRAWFORD.
